UNITED STATES PATENT OFFICE

2,027,588

APPARATUS FOR TREATING THE LARGE
INTESTINE

Edward F. Hannon, Tulsa, Okla.

Application September 5, 1933, Serial No. 688,117

11 Claims. (Cl. 128—227)

My invention relates to new and useful improvements in means for and methods of treating the large intestine and of administering drugs, chemicals, bacteria and the like to it and to the patient through it, and of cleansing it, and treating its walls and removing therefrom undesirable substances; to the effect that the intestinal tract may be permitted to function normally or with increased efficiency and local conditions in said large intestine be improved and the general health of the patient augmented; and has for its object the attainment of a more thorough treatment as aforesaid, a more positive action on said large intestine and on matter therein and on the walls thereof, and a more efficient control of the various processes involved in said treatment.

With the above and other objects in view which will appear as the description proceeds, my invention consists in the novel features hereinafter set forth in detail, illustrated as to apparatus in the accompanying drawing, and more particularly pointed out in the appended claims.

25 Referring to the drawing in which numerals of like character designate similar parts throughout the several views:

Fig. 1 is a diagrammatic view of the large intestine in a human being.

30 Fig. 2 is a view in perspective of my apparatus which is shown in a portable form.

Fig. 3 is an enlarged top plan view of my central by-pass control chamber.

Fig. 4 is a view of the same in cross section 35 on line A—A of Fig. 3.

Fig. 5 is an enlarged top plan view of my gas trap and by-pass chamber, which, when in operating position as shown in Fig. 2, would be a view in side elevation.

40 Fig. 6 is a view of the same in cross section on line C—C of Fig. 5.

In the drawing 1 represents a tank having three compartments 2, 3, and 4 each having an outlet duct numbered respectively 5, 6 and 45 7 leading to a common duct 8, and with each of said ducts having therein a valve numbered respectively 9, 10, 11, and 12. In all of said ducts a section thereof may be made of transparent material such as glass through which the operator may conveniently make observations 50 of the liquid condition in the ducts, and the remainder thereof made of flexible tubing such as rubber; or the valves and their connections may be made of glass and the tubing of rubber 55 adapted to be slipped over the glass connection,

which is the preferred form of portable construction for all of the valves and connections and tubing used throughout the apparatus.

Duct 8 empties into the side of a central by-pass control chamber 13, common to a number 5 of ducts which all connect into at as hereinafter described.

Duct 14 is inserted in the side of chamber 13 and leads to and from it and has a valve 15 therein which controls the flow of liquid 10 through said duct 14 in either direction. A glass observation tube 16 of a few inches in length is inserted into the end of duct 14 as part thereof through which the flow of substances through the tube may be observed and which 15 permits the operator to be advised of conditions encountered in the large intestine.

A cecum tube 17 with the usual outlets adjacent to its end, is connected to the glass observation tube 16, either directly as shown or 20 intermediary through an additional length of flexible tubing, whichever the operator may prefer.

A pressure gun or bulb 18 is connected into the side of chamber 13 through duct 19 which has a 25 valve 20 therein.

Leading from the side of chamber 13 is a primary discharge duct 21, with valve 22 therein.

The chamber 13 is constructed with its inlets and outlets so that the top of the chamber 30 serves as a dome wherein gas may be trapped. A secondary siphon duct 23 runs from the dome of chamber 13 and has a valve 24 therein. Duct 23 not only acts as a siphon through which gas may be drawn from the dome of chamber 13, 35 but serves the purpose of injecting a fluid into said chamber 13 as will later be explained.

Both the primary discharge duct 21 and the secondary siphon duct or dome line 23 lead into a gas trap and by-pass chamber 25 from which a 40 waste duct 26 empties into a waste receptacle 27. The waste duct 26 may also serve as a siphon duct, supplementing ducts 21 and 23 in effect being a continuation thereof, when duct 23 is not being used as a circulating or recycling or 45 feed-back duct.

Into gas trap and by-pass chamber 25 is looped a circulating duct 28, with valve 29 therein, one end of which duct is located in the side of said gas trap and by-pass chamber 25 and the 50 other end located in the bottom thereof.

The entire apparatus shown is designed so as to make it portable and easily set up and taken down, and with that in view I have caused the three separate tanks 2, 3 and 4 to be made as 55

- three compartments of one tank 1, as generally three tanks are used in operation, and have made all of the various ducts of rubber tubing, except the various connections in said ducts, and 5 furthermore, have located all control valves in the entire system so that the operator may easily manipulate the entire apparatus, and have mounted the central control chamber and all of the valves related thereto on a base 30.
- 10 When the apparatus is to be used, a table 31 is provided whereon the patient to be treated may recline in the position usually assumed in such operations, and tank 1 is positioned at the table and above it so that its contents may gravitate into chamber 13 and thence thru the cecum tube into the large intestine of the patient. The base 30 with the apparatus mounted thereon, is then placed on the table mentioned and the entire apparatus connected as shown in 15 Fig. 2 of the drawing. Tubes 21 and 23 with the gas trap and by-pass chamber 25 depending therefrom, are hung over the side of the table in a position wherein a gas entering chamber 25, from line 21, will rise and enter line 23, and the 20 end of tube 26 placed in receptacle 27 which may be set on the floor, in which position liquid may be caused to gravitate from chamber 13 into receptacle 27.
- 25 For the purpose of withdrawing a specimen 30 from the patient, I have provided a three way valve 32 in observation tube 16 with line 33 leading therefrom, so that matter may be withdrawn from either side of valve 32, and may enter line 33 from whence it may be removed.
- 35 In operation, with all connections made and with the apparatus in place, valves 9, 10, 11, 15, 22, and 24 are closed and the tanks 2, 3 and 4, or any of them, are filled or partially filled with such liquid or liquid substance or matter held 40 in suspension in said liquid as it may be desired to inject into the large intestine of the patient. The valve or valves 9, 10, 11 and 24 are then opened to permit chamber 13 to be filled with the liquid from the desired tank or tanks, after 45 which valve 24 may be closed or partially closed, and bulb 18 worked to exhaust the air in it and fill said bulb and tube 19 with liquid, after which valve 20 is closed, or the whole system may otherwise be filled with the liquid desired. 50 Valve 22 is then opened to permit duct 21 or ducts 21 and 26 to fill, after which it is closed, whereupon all is in readiness for use.
- 55 The patient to be treated is then placed on the table and positioned in the conventional manner and the cecum tube 17 injected in the usual manner into the patient's large intestine, and in general is manipulated therein the same as has heretofore been customary, that is run back and forth a little distance at a time, flushing the large intestine with liquid from the aforesaid tank or tanks as the cecum tube is gradually injected further into the large intestine until the cecum itself is reached, in which operation a number of treatments at different 60 times are generally necessary before the tube can be injected fully into the large intestine, all of which is well known to those engaged in the practice. This operation is controlled by the manipulation of the various valves.
- 65 70 In addition to the removal of matter from the large intestine by flushing, or by injection of liquid and removal of liquid and matter by draining or by expelling under pressure created in the patient, I use a vacuum to pull back the 75 liquid into the cecum tube and to draw into

it the matter to be removed from the large intestine. By opening valves 12 and 15, I can apply pressure to flow the liquid into the large intestine at the desired point, and then by closing valve 12 and opening valve 22 I can apply a suction at said point to draw back the liquid and the matter to be removed. Also by closing all valves except 15 and 20 and manipulating bulb 18 I can apply additional pressure in the cecum tube and large intestine when it is desired to increase the pressure over that provided by the static head of the liquid from the tank, and by then opening valve 22 I can create a suction, thus working the liquid in and out of the cecum tube and permitting the forward and reverse currents to play upon the desired point in the large intestine. This control of the currents greatly assists in the opening up of the large intestine and the removal of matter therefrom, particularly when the sacculations of the 20 large intestine are being cleaned out or the coating on the wall of the large intestine is being removed or scaled away as is possible with my method of operation.

Moreover, under my method, gas in the patient may be drawn off into the central by-pass control chamber 13 from which it may be removed through tube 23 without unduly interfering with the operation.

When desired, I control the vacuum action 30 to automatically set up or bring about a sudden release or partial release of the suction in the cecum tube and then cause a sudden resumption of the suction to occur, so that a jerking movement is caused in the current entering the 35 cecum tube from the large intestine with the result that a jarring effect is exerted on the matter in the large intestine or on its walls, which causes such matter to become broken up or loosened from the walls of the large intestine 40 and in condition to slough off and to be drawn into the cecum tube. The apparatus shown is designed to accomplish this in the following stated manner. When the intake line 8 is closed and line 19 is dormant and line 14 is open and 45 the siphon is working thru tubes 21 and 26, drawing fluid from the patient and gas is coming from the patient or is present in the system, a part of the fluid and gas flowing thru tube 21 may be caused to enter tube 23 from 50 the gas trap and by-pass chamber 25 and to be returned thru tube 23 back into the central by-pass control chamber 13 by opening valve 24 in duct 23 and opening valve 29 in tube 28. Under circumstances the feed-back may be 55 brought about by merely opening valve 24, particularly if the flow of fluid coming from the patient is retarded or is heavy and the column of fluid in duct 23 is light enough for the descending column of fluid in duct 21 to raise by its 60 suction, nor is it essential that valve 29 be present in duct 28 for said duct may remain open to function upon the opening of valve 24 in duct 23 as aforesaid. When said feed-back or return flow is in operation the liquid and gas enters 65 tube 23 alternately, forming in the tube a flowing column in which short slugs of liquid are separated by gas pockets, and in this condition the liquid and gas are emptied into chamber 13, which is under these conditions a part of the 70 siphon system of duct 21. The alternate injection of liquid and gas into said chamber sets up sudden fluctuations in the degree of vacuum present in chamber 13, as when a column of gas enters and is drawn into the line 21 the 75

5 weight of the descending column of fluid creating the siphon is lessened and when an alternate column of liquid enters and is drawn into said line 21, the weight of the descending column 10 of liquid creating the siphon is increased. The degree of fluctuations or the intensity thereof will vary with the weight and velocity of the column creating the suction and with the amount and rate of flow of gas into the suction line, 15 and relatively wide fluctuations in the degree of vacuum may under certain conditions be used to advantage in treating the patient. This fluctuation in the degree of vacuum present in chamber 13 is of course transmitted to the cecum tube and likewise occurs therein with the result that the speed at which the fluid enters into the cecum tube from the intestine is subjected to sudden fluctuations, so that the jarring or jerking movement aforesaid is set up with 20 the effect above noted. In such an operation tube 26 acts as a drain tube and does not act as a part of the siphon system.

25 The vacuum is also used when it is desired to draw off from the large intestine matter which has been temporarily introduced at any particular place therein, as for instance certain medicines or bacteria, and permits a positive and instantaneous withdrawal of such matter.

30 Bulb 18 may also be manipulated while liquid is flowing into the large intestine under force of gravity, to cause sudden increase in pressure or a jarring effect on the liquid, when desired.

Having thus fully disclosed my invention, what I claim and desire to secure by Letters Patent is:

35 1. In an apparatus used for treating the large intestine a central by-pass control chamber, a gas dome therein wherein gas may be trapped, a valve controlled opening in said dome, a valve controlled inlet and outlet in said chamber to a cecum tube.

40 2. In an apparatus for treating the large intestine having a central by-pass control chamber, a plurality of valve controlled openings therein, a gas dome in said chamber wherein gas may be trapped and a valve controlled opening in said dome.

45 3. An apparatus, used in treating the large intestine, comprising a central by-pass control chamber, a dome therein, a valve controlled opening in said dome, a valve controlled inlet in said chamber adapted to be connected into a liquid transporting line, a valve controlled inlet and outlet into and out of said chamber adapted to be connected into a cecum tube; a valve controlled outlet in said chamber adapted to be connected into a suction line and an inlet and outlet opening in said chamber adapted to be connected into a pressure and suction line.

55 4. An apparatus, as claimed in claim 3 and

with said valve controlled opening being connected into said suction line.

5 5. In an apparatus used for treating the large intestine, a central by-pass control chamber, a dome therein, a valve controlled line connected into said dome, a valve controlled liquid intake line connected into said chamber, a valve controlled cecum tube line connected into said chamber, a valve controlled siphon line connected into said chamber, and means of circulating a part of the fluid passing thru said siphon line back into said siphon line through said central by-pass control chamber.

10 6. The combination of a cecum tube used in treating the large intestine, and means of creating a suction therein, and means of automatically subjecting said suction to sudden changes in its degree of vacuum.

15 7. In an apparatus used in treating the large intestine, a central by-pass control chamber, a 20 dome for trapping gas therein, a valve controlled opening in said dome, a valve controlled inlet in said chamber adapted to be connected into a liquid transporting line, a valve controlled inlet and outlet into and out of said chamber 25 adapted to be connected into a cecum tube, and a valve controlled outlet from said chamber adapted to be connected into a discharge line.

8. In an apparatus used in treating the large intestine, a discharge line connected into a 30 cecum tube and means of automatically feeding back into said discharge line a portion of the fluid previously passed therethru.

9. In an apparatus used in treating the large intestine, wherein a discharge line is employed 35 connected to a cecum tube, means of automatically feeding back into said discharge line a portion of the fluid previously passed therethru and means of starting said feed back, one of which means is a looped circulating duct connected into said discharge line.

10. In an apparatus used in treating the large intestine, a discharge line connected into the cecum tube and means of automatically feeding back into said discharge line a portion of 45 the fluid which may have previously passed therethru, one of which means is a tube, one end of which is connected into said discharge tube line at one place therein with the other end of said tube connected into said discharge 50 line at another place therein lower than said first mentioned place.

11. In an apparatus for treating the large intestine wherein a cecum tube is employed, a central by-pass chamber having a dome therein 55 wherein gas may be trapped and an outlet from said dome, a duct connecting said chamber with said cecum tube, and a valve controlled drain tube connected into said duct.

EDWARD F. HANNON.
